UNITED STATES PATENT OFFICE.

DORA E. SLOCUM, OF KUNER, COLORADO.

STEAM-BOILER.

1,697,886.

Specification of Letters Patent. Patented May 26, 1914.

Application filed December 17, 1913. Serial No. 807,275.

To all whom it may concern:

Be it known that I, DORA E. SLOCUM, a citizen of the United States, residing at Kuner, in the county of Weld and State of Colorado, have invented certain new and useful Improvements in Steam-Boilers, of which the following is a specification, reference being had to the accompanying drawings.

10 This invention relates to new and useful improvements in washing apparatus and more particularly to a steam boiler and the primary object of the invention is to provide a device of this character which will 15 be most efficient in removing dirt from and thoroughly cleansing garments placed in the device.

A further object of the invention resides in providing an improved device which is 20 simple and durable in construction, inexpensive to manufacture and one which will be very efficient and useful in operation.

With these and other objects in view, the invention consists in the novel features of 25 construction, combination and arrangement of parts as will be hereinafter referred to and more particularly pointed out in the specification and claim.

In the accompanying drawing forming a 30 part of this application, Figure 1 is a vertical section through a device constructed in accordance with my invention. Fig. 2 is a bottom plan view of the tubular member used in connection with the device; and 35 Fig. 3 is a perspective view of the supporting device for the tubular member.

In describing my invention, I shall refer to the drawing in which similar reference characters designate corresponding parts 40 throughout the several views and in which—

1 indicates a boiler proper of the usual or any preferred type, provided in the wall thereof adjacent the bottom, with a faucet 2 for the removal of the water therein at pre-determined times. Also mounted centrally 45 on the bottom of the boiler is a supporting member 3 which is formed of a section of a pipe, the purpose of which will be herein-after and more particularly set forth. A

50 tubular member 4 is also provided, the lower end of which is enlarged, as shown at 5 to fit over the supporting pipe section 3 and a central ring portion 6 supported in the flared or enlarged end 5 by means of radial 55 arms 7 directly receives the pipe supporting section 3 therein. An enlarged portion 8

is formed on the pipe section 3 and affords a means for supporting the flared end of the tubular member 4 above the bottom of the boiler, whereby water and steam may 60 readily enter the same and rise upwardly through said tubular member. The extreme upper end of the tubular member 4 is provided with a sprinkling or nozzle-like head 9.

65 Formed on the inner wall of the boiler 1 in a plane above the plane of the upper end of the supporting member 3, is an annular supporting flange 10 and arranged in the boiler to rest on said flange, is a perforated 70 tray 11. This tray is provided with an annular wall so as to inclose the garments received thereon and the bottom of the tray proper is provided with an opening through which the tubular member 4 is disposed.

75 A lid or outer closure 12 is provided for the boiler 1 and an auxiliary wall or shield 13 is provided on the inner face of said lid or top against which the water from the bottom of the boiler is directed when sprayed 80 from the nozzle or sprinkling head 9. Openings 14 and 15 are provided respectively in the members 12 and 13 for the escape of steam from the device when desired.

85 In operation, after the boiler has been filled to the desired point with fresh water, and the parts of the device properly applied in position, garments are placed on the tray and the lid properly applied to the device. The boiler thus filled, is placed on a heating apparatus and when the water in said boiler reaches boiling point, the steam arising therefrom will be directed through the enlarged portion 5 of the tubular member and conducted upwardly through the latter. 90 This will cause a partial vacuum which will draw the heated water in the bottom of the boiler upwardly to be sprayed against the lid or closure of the device, through the medium of the sprinkling head 9. The water 95 will then be directed downwardly and will percolate through the garments on the tray. The tray being perforated, will permit the water which percolates through the garments to pass therethrough and again drop to the lower portion of the boiler. This will continue for a short while and the operator may at any time, permit the dirty water in the bottom of the boiler to be removed by the opening of the faucet 2. Clean water 100 may then be applied without the removal of the parts of the device shown and described.

From the foregoing it will be seen that I have provided an improved boiler which will positively clean the garments which are applied therein. It will further be seen that 5 the device is one which is simple and durable in construction, inexpensive to manufacture and one which will be very efficient and useful in operation.

While I have particularly described the 10 elements best adapted to perform the functions set forth, it is obvious that various changes in form, proportion and in the minor details of construction may be resorted to without departing from the spirit 15 or sacrificing any of the principles of the invention.

Having thus described this invention, what I claim is:—

In a boiler of the class described, a re-

ceptacle, a tubular supporting member 20 mounted on the bottom of the receptacle and provided with a shoulder adjacent its upper end, a tubular member having its lower end flared disposed within the receptacle, a ring carried by the flared lower end of the tubular member for engagement with the shoulder of the supporting member whereby to dispose the lower end of the tubular member in a plane above the bottom of the receptacle, a tray removably mounted in the 25 receptacle, and a closure for said receptacle.

In testimony whereof I hereunto affix my signature in the presence of two witnesses.

DORA E. SLOCUM.
